[57] CLAIM

The ornamental design for a microfloppy disk drive, as
shown and described.

DESCRIPTION

FIG. 1 is a front perspective view of the microfloppy
disk drive showing my new design;

FIG. 2 is a front elevational view thereof on a reduced
scale;

FIG. 3 is a rear elevational view thereof on a reduced
scale;

FIG. 4 is a top plan view thereof on a reduced scale;

FIG. 5 is a side elevational view thereof on a reduced
scale, the opposite side being a mirror image;

FIG. 6 is a bottom plan view thereof on a reduced scale.
